UNITED STATES PATENT OFFICE.

SAMUEL H. HOPKINS, OF PROVIDENCE, RHODE ISLAND, ASSIGNOR TO WM. C. GREENE,
JNO. T. MAURAN, AND CHAS. JACKSON.

STUD AND BUTTON FASTENING.

Specification of Letters Patent No. 12,725, dated April 17, 1855.

To all whom it may concern:

Be it known that I, SAM'L. H. HOPKINS, of Providence, in the county of Providence and State of Rhode Island, have invented a new and Improved Fastening for Shirt-Studs, Buttons, &c.; and I do hereby declare that the following is a full, clear, and exact description of the same, reference being had to the annexed drawings, making a part of this specification, in which—

Figure 1, is a back view of my improved fastening applied to a shirt stud. Fig. 2, is a longitudinal section of the tube of the stud, showing the spiral spring within it. Fig. 3, is a side view of the fastening.

Similar letters of reference indicate corresponding parts in the several figures.

The nature of the invention consists in the peculiar construction of the fastening, which will be fully shown and described hereafter.

To enable others skilled in the art to fully understand and construct my invention, I will proceed to describe it.

A, represents the front disk or plate of the stud, and B, is a tube attached to the back part of the disk or plate A, at about its center and projecting from it at right angles as shown in Figs. 2 and 3, said tube forming the shank of the stud.

At the outer end of the tube B, there is a pin (a) which passes transversely across the end of the tube, and within the tube there is fitted a spiral spring (b) as shown in Fig. 2.

The outer end of the tube B, is slotted at two opposite points and a small bar (c) is inserted in the slots, designated by (d) Figs. 1 and 2, and between the spring (b) and the pin (a), the pin fitting in a recess (e) in the outer edge of the bar and at its center, as clearly shown in Figs. 1 and 2. The bar (c) has knobs (f) one at each end, which knobs prevent the bar from passing out of the slots (d).

The spiral spring (b) keeps the recess (e)

in the bar (c) over the pin (a) as shown in Fig. 2.

The stud is adjusted in the proper eyelet holes in the garment by depressing or shoving the bar (c) toward the disk or plate A, till the recess (e) is free from the pin (a), see dotted lines Fig. 2. The bar is then shoved outward till one of its knobs (f) reach the side of the tube B, as shown by the red dotted lines in Fig. 2, and the bar and tube may then be inserted in the eyelets, and when through them, the bar (c) is shoved back to its original position the disk or plate A, being on the outer side of the garment and the bar (e) on the inner side, the tube B, being in the eyelet holes, see Fig. 3, (a') representing the eyelet holes of a garment.

The above invention is simple, and effectually secures the stud or button to the garment and there is no danger of the bar (c) being casually displaced so as to allow it to pass out of the eyelets.

Having thus described my invention, what I claim as new and desire to secure by Letters Patent, is,

The construction of the fastening as herein shown and described, viz, having the shank of the stud or button, formed of a tube B, which contains a spiral spring (b) and having a bar (c) fitted in slots (d) in the outer end of said tube and between the outer end of the spiral spring (b) and a pin (a) attached to the outer end of the tube. The outer side of the bar (c) being provided with a recess (e) which, by means of the spring (b) is kept over the pin (a) and the bar (c) consequently secured in a transverse position with the tube B.

SAMUEL H. HOPKINS.
